UNITED STATES PATENT OFFICE

2,142,806

METHOD OF OPERATING VAPOR JET
VACUUM PUMPS

Peter Schlumbohm, New York, N. Y.

Refiled for abandoned application Serial No. 65,959, February 27, 1936. This application December 13, 1937, Serial No. 179,457. In Germany May 4, 1933

3 Claims. (Cl. 230—102)

This application is a refile of my former application, Ser. No. 65,959, filed Feb. 27, 1936, and later abandoned.

The present invention relates to a method of improving the vacuum effect of ejector pumps. In such ejector pumps the vapor of substances with low vapor pressure, like mercury, oil or water, leaves a "nozzle" and enters into a "diffusor". The free space between the edge of the nozzle and the wall of the diffusor forms an annular channel and is called the "suction channel". The nozzle is inserted into the "suction chamber" which is in open connection with the space to be evacuated. The dimensions of the suction channel influence greatly the degree of vacuum obtainable by a certain vapor; but even at the optimum conditions chosen for the suction channel, there is an "end vacuum", i. e. a limit of a degree of vacuum obtainable by that vapor. The end vacuum reachable with mercury and oil is satisfactory for all practical purposes. When using water steam, however, it is difficult to reach in a single stage ejector a vacuum below 2 mm. With very complicated arrangements, e. g. four stage ejectors with condensation between the single stages, and requiring high steam pressures, it was possible to reach 0.4 mm. Hg vacuum.

By my present invention it is possible to reach in a single stage and with the extremely low steam pressure of less than one atmosphere abs. a vacuum of 0.1 mm. Hg, while using water steam as propellant vapor.

The invention relates further to the construction of an apparatus, in which the new method may be applied.

The invention is illustrated in the accompanying drawing, which may be considered as diagrammatic so as to include other constructions.

Fig. 1 is a sectional view illustrating the operation of an ejector.

Fig. 2 shows, mainly in cross section and partly in view, an ejector pump which actually has been built all in glass and the drawing is based on the constructional drawing of the working model, except for the dimensions of jet, diffusor, water jet pump and liquid columns.

The invention was the consequence of a theoretical deliberation concerning the mechanism of the vacuum effect of a steam jet, and it was a great satisfaction to see the theoretical conclusion confirmed by the very first experimental attempt made to prove it. The conclusion was (see Fig. 1) that the end vacuum would

be reached at the moment when part of the steam 2, leaving the nozzle 1 and entering into the diffusor 5, would diffuse back into the suction channel 3 and form there a vapor cushion of steam, and that such a stationary vapor cushion 5 would make it impossible for an air molecule to diffuse from the suction chamber 4 into the suction channel 3 to be carried away by the steam 2 into the diffusor 5. The invention now is: to absorb this cushion of vapor chemically. 10 When this is done, the end vacuum is improved greatly, in the case of water vapor to 0.1 mm. Hg.

Following the invention, the absorption of the vapor cushion in the suction channel is effected by a chemical absorbing means—specific 15 for the kind of vapor applied—which enters continuously into the suction channel 3 (see Fig. 2). In the case of water steam as propellant vapor, the chemical absorbing means may be constituted by hygroscopic fluids like sulphuric acid, 20 potassium hydroxide—or sodium hydroxide—solutions or the like. In Fig. 2 the sulphuric acid enters from atmospheric pressure through tube 13 into a distributor 14 arranged within the vacuum space 22 and trickles through holes 16 25 into the suction chamber 4 of the steam nozzle 1; as indicated by the tail-end arrows the sulphuric acid flows into the suction channel 3, then into the diffusor 5, then into a liquid trap 12, from which it may be eliminated by a water jet 30 pump 7, leaving through the off-water tube 23. The air to be pumped by the steam jet 1 is characterized by feather-end arrows, entering the vacuum space 22 through a suction tube 19 and leaving space 22 through suction chamber 4, 35 suction channel 3, diffusor 5, pre-vacuum space 21, air-suction tube 8 of the water jet pump 7, and finally through the off-water tube 23.

When checking up the improvements obtained by introducing chemical absorbing means into the suction channel 3, I found that such absorbing means were also effective in the diffusor 5, and I conceived the idea to absorb the total amount of steam entering into the diffusor 5 instead of condensing the vapor as usual in steam 45 ejectors. This part of the invention stands on its own merit, independent of the step of introducing absorbing means into the suction channel, and may prove to be of general usefulness. However, it is of special value in the present 50 case in connection with the other part of the invention as mentioned above, as it increases the efficiency of the steam ejector itself, independent of the above mentioned new vacuum effect. It was found that chemical absorbing means for 55

absorbing the steam in the diffusor, should not be introduced through the suction channel, as such a procedure would flood the suction channel with liquid. Thus only the small amounts 5 of absorbing liquid which are required for absorbing the vapor cushion in order to improve the vacuum effect are introduced through the suction channel.

As illustrated in Fig. 2 the body of the pump, 10 which comprises the pre-vacuum water jet pump 7, the high-vacuum pump 1, 3, 4, 5 and the suction tube 19 is constituted by an outer casing 20, the inside space of which is subdivided into the pre-vacuum space 21, in which a 12 mm.-15 mm. 15 pressure is created and maintained by the water jet pump 7, and into the high-vacuum space 22, in which the steam ejector creates and maintains a vacuum of e. g. 0.1 mm. The two pressure spaces 21 and 22 are separated from each other 20 by a liquid trap in the communicating annular spaces 17 and 18. This arrangement makes it possible to introduce absorbing means into the pre-vacuum space 21 for the absorption of the steam without using the suction channel for 25 introducing them. As shown in the Fig. 2 the distributor 14 for the absorbing liquid has holes 15 through which the sulphuric acid may trickle over the outer wall of the water cooled double-walled body 10, which is arranged vertically, 30 being with its upper part in the high-vacuum zone 22 and with its lower part in the pre-vacuum zone 21. On its way over the outer wall of body 10 the absorbing liquid will in the high-vacuum zone 22 be useful for absorbing vapors 35 coming from an evaporator through tube 19, a process as described in my U. S. A. Patent No. 1,894,893. Passing through the liquid trap 17, 18—part 18 being built as an overflow—the absorbing liquid, rinsing over the outer wall of body 40 10, enters into the pre-vacuum zone 21 and absorbs the vapor which comes from the diffusor 5, as indicated by the feather-end arrows. The absorbing liquid, diluted by the absorbed vapor, drips to the bottom of casing 20, where it joins 45 the absorbing liquid, which was introduced into the suction channel, and from where it flows through liquid trap 12 into the water jet pump 7 and its off-water tube 23. The cooling water for cooling body 10 enters through tube 9 and then serves to run the water jet pump 7. Steam for the nozzle 1 enters through tube 6.

I found that a steam pressure as low as about 190 mm. Hg, corresponding to about 65° C. hot water, is sufficient to obtain 0.1 mm. vacuum 55 under the conditions as described above. Such a pressure is only a fraction of the pressures now applied in steam ejector vacuum pumps, and this feature of the invention involves a great economy.

The economy of the apparatus as shown in the drawing may be improved by withdrawing the diluted absorbing means from container 12 for 60 reconcentration purposes, instead of letting the diluted acid flow into a water jet pump. For 65 small capacities, however, it does not pay to re-

cover the absorbing liquid, and then the further dilution by the off-water of the water jet pump is quite convenient for carrying the sulphuric acid or the like away into the sewer system in a highly diluted form.

The apparatus as shown in Fig. 2 combines the features of the present invention with the features of my U. S. Patent 1,894,893. In said patent, however, a mechanical high vacuum pump of the type of a rotary oil pump or of the type of a mercury vapor pump was required to withdraw the air from the high-vacuum absorber. By the present invention all functions are achieved by two chemicals only: water and the absorbing liquid. If the new high-vacuum steam ejector 15 of the present invention is combined with a high-vacuum absorber for water vapors as described in U. S. Patent 1,894,893, said combination being shown in Fig. 2 of the present patent application, then the capacity of the steam ejector 1 can be chosen very small, as only small amounts of air are to be pumped. The main pumping job is done in that case by the absorbing liquid which trickles through the holes 15 over the outer wall of the water cooled body 10 within the high-vacuum space 22, where it is exposed to water vapors coming from an evaporator through tube 19. It can be demonstrated that the flow of such water vapors into the high-vacuum space 22 through tube 19 is at evaporator 30 temperatures of around 0° C. only possible if in space 22 the partial pressure of air is in the order of magnitude of a fraction of a millimeter. Being able to pump air to this degree is the importance of the present invention. At such low evaporator temperatures water has a huge specific vapor volume (at 0° C. 18 gr. of water evolve about 3,000 litr. of vapor) and the great flow speed of such water vapors as required for an efficient pumping can only be obtained if the 40 absorber is free of air.

Having now described my invention and indicated by way of example the manner in which it is to be performed,

What I claim is:

1. In the method of operating a steam vapor jet vacuum pump the step of introducing continuously into the pump a fluid adapted to absorb the propellant vapor applied, the step of absorbing propellant vapor by means of said absorbing fluid and the step of withdrawing from the pump said absorbing fluid diluted by absorbed propellant vapor.

2. In the method as claimed in claim 1, the step of introducing said absorbing fluid into the suction channel of the vapor jet to absorb there propellant vapor which diffused back into the suction channel.

3. In the method as claimed in claim 1, in which the steam vapor leaving the jet enters into a pre-vacuum zone, the step of introducing said absorbing fluid into the pre-vacuum zone of the vapor jet to absorb the propellant vapor which leaves the diffusor of the vapor jet.

PETER SCHLUMBOHM.
